UNITED STATES PATENT OFFICE.

EDWARD O. TINSLEY, OF BROOKLYN, NEW YORK, ASSIGNOR TO ROBERT GAIR COMPANY, OF BROOKLYN, NEW YORK, A CORPORATION OF NEW YORK.

COLLAPSIBLE DISPLAY-CONTAINER.

1,245,531.

Specification of Letters Patent.

Patented Nov. 6, 1917.

Application filed March 31, 1917. Serial No. 158,839.

To all whom it may concern:

Be it known that I, EDWARD O. TINSLEY, a citizen of the United States, residing in Brooklyn, in the county of Kings and State 5 of New York, have invented certain new and useful Improvements in Collapsible Display-Containers, of which the following is a specification.

This invention relates generally to collapsible-boxes, and more especially to knock-down boxes that may be flattened out for purposes of shipping the same in quantities; that may be practically instantly assembled for use as shipping containers; and as 10 quickly turned into open and display-containers supported in such manner that the goods therein will be displayed in an attractive and pleasing manner to the purchasing public. Such containers may be 15 formed of any desired sheet material but usually and preferably for cheapness are formed of thin cardboard, stamped out into two separate normally non-attached coacting-blanks; which when folded into proper 20 form and interlocked, will form the complete containers either for purposes of shipment with the goods therein, or for purposes of counter or window display, when retailed.

The main and fundamental object of my 30 invention herein disclosed is to form a cheap and efficient knock-down shipping, and display-container, in which the hand-work and manipulation necessary to form the same; and also to assemble the same into proper 35 form to be filled, will be reduced to a minimum. In all of such boxes or receptacles hitherto known in the art, expert labor has been required to form the same, and considerable glue or other suitable cementing 40 material has of necessity been used in the formation thereof; which cementing material could only be applied by high-class skilled labor; but in my improved form of container herein shown, described and 45 claimed, there is only one small glued, or otherwise secured joint, in the entire structure, and the parts thereof can be quickly and easily assembled into a retainer form, by the cheapest of unskilled labor and as 50 quickly, easily and cheaply disassembled and folded flat into proper shipping small space; whereby such container may be used over and over again at a minimum cost.

These and other features, capabilities and 55 advantages of the invention, will appear

from the subjoined detailed description of the specific embodiments therein shown, described and claimed in the following specification, of which the accompanying drawings form a part; wherein similar letters or 60 numerals of reference designate like or equivalent parts, wherever found throughout the several views; and in which:—

Figure 1 is a front top corner view in perspective, of my improved form of collapsible box or container in the closed position, as it appears when filled with goods 65 and ready for shipment.

Fig. 2 is a like front corner view of such container shown closed in Fig. 1, in the open and display position, ready to be placed in a show-case or window, in view 70 of the public so that the goods therein will be attractively brought to view.

Fig. 3 is a plan view of the inner body 75 of box forming portion of such container or receptacle, in blank form, struck and scored for bending by suitable dies, etc.

Fig. 4 is a front corner view in perspective in detail of the main body, inner-box 80 forming blank shown in Fig. 3, bent up into box form ready to be placed in the rectangular combined secured auxiliary cover and tilting-base support-member;

Fig. 5 is a view similar to Fig. 3 of the 85 blank out of which is formed the outer auxiliary binding cover and combined base support member, which when superposed upon the main body box or receptacle formed from the blank A, shown in Fig. 3, 90 constitutes the entire structure of my improved knock-down, collapsible, shipping and display box or container, herein shown, described and claimed.

Fig. 6 is a view similar to Fig. 4 of the 95 blank shown in Fig. 5 bent up into proper form to receive the main body portion of the receptacle shown in Fig. 4; and

Fig. 7 is a view of the entire box or receptacle taken in central vertical section on 100 substantially the line 7—7 of Fig. 2, looking from the left thereof in the direction of the arrow; the auxiliary cover and tilting base support being shown in full lines, about to be put into the display supporting position 105 shown therein in dotted lines.

Referring to the drawing:—

As shown in Fig. 3, the main-body inner box-forming blank of the receptacle designated by the reference letter A, comprises 110

the central bottom portion 11, the end portions 12 and 12', the front portion 13 and the back portion 14, such front and back portions being provided at the ends with the 5 securing-tabs 13' and 14' respectively, and having the main display cover 15 extending from the back piece 14. And such blank is scored, preferably outwardly upon the lines 16, 17, 18 and 19, so that the same can be 10 bent up into the rectangular-box form indicated in Fig. 4, with the tabs 13' and 14' exterior to the end pieces 12 and 12'. The tabs 13' and 14', preferably narrow from their bases at 19, outwardly so as to leave 15 between the same and the end pieces 12 and 12', outwardly flaring slots 16', (as clearly indicated in Fig. 3) and the outer end lines 17 of the display cover 15, extend a short distance beyond the score lines 19 of the main 20 body portion of such blank, so that when folded down into the closed position shown in Fig. 1, the display cover 15 will extend over the tops of the side members 12 and 12', as clearly indicated at 20 of Fig. 1.

25 The outer border rectangular binder and combined outer auxiliary cover and inclined base support member, indicated by the reference letter B, which is superposed upon the main-body rectangular-box portion formed 30 from the blank A, comprises the combined auxiliary outer cover and supporting base portion 21, having the outer securing-flap 22, the inner tilting base-support portion 23, and the border band back-piece 24 in line 35 with the end band member 25, the front band member 26, the end member 27 and the securing tab 28. Such members 24, 25, 26, 27 and securing-tab 28 being scored upon the outward side by the scoring lines 29 similar 40 to the lines 17, 18 and 19 of Fig. 3, and the main-body portion thereof, made up of 21, 22, 23 and 24, is also scored on the lines 30, 31 and 32, in like manner.

45 The blanks having been formed by suitable dies and blanking mechanism into the shapes shown in Figs. 3 and 5; the securing rectangular body binder-portions of B (24, 25, 26, 27 and 28) is bent upon its four scorings 29, and the tab 28, being supplied 50 with glue or suitable cementing material is then glued to 24 at the point marked 33 of 24, (Figs. 5 and 6), so as to be bent into the rectangular form clearly shown in Fig. 6; while for purposes of shipment of the blanks 55 in bulk, such rectangular band-portion can be bent down flat; and in place of glue or like cementing material the tab 28 may be secured at 33 by metallic or other suitable fastening with equal effect.

60 To assemble the blanks A and B into box-form for the reception of the goods to be shipped and put on sale; the blank A is taken in hand by the worker, and the ends 12 and 12' are bent up into the right angled 65 upright position shown in Fig. 4, and the

tabs 13' and 14' being bent outwardly over such end pieces 12 and 12'-(as clearly indicated in Fig. 4), such rectangular box-receptacle so formed, is passed down into or up through the exterior-binder rectangular portion of B formed by 24, 25, 26 and 27, which will retain such central-box or body portion A in the form shown in Fig. 4; and the box being filled with the goods, the combined auxiliary outer-cover and tilt-base support, 75 21, 22 and 23 being turned forward, up over the main display cover 15, and the securing end 35, passed down into the space 36 (Figs. 1 and 2) between the outer face member 26 of the blank B, and the adjacent front-wall 80 member 13 of A, the complete box or receptacle, with its contents, will be in the closed position shown in Fig. 1, and ready for shipment.

When it is desired to place the goods upon 85 exhibition, the outer auxiliary-cover and tilting base support (21, 22 and 23) is bent backward, into the position shown in Fig. 7; and the securing end 22, being bent reversely 90 to its position when in the closed box position, shown in Fig. 1, and slipped up into the space between 26 and 13, from the bottom, the auxiliary cover and tilt-base-support will be in the position shown in dotted lines in Fig. 7, and in full lines in Fig. 2, whereby 95 the box containing the goods to be displayed, will be raised at the rear, and thus tilted forward to bring the goods therein more perfectly to view; and at the same time the main inner display cover 15, usually supplied with suitable advertising matter, is 100 thrown up into the position shown in Figs. 2 and 7.

It is evident that many changes and modifications in the construction of my improved 105 collapsible shipping and display box or receptacle herein shown, described, and claimed, may be made without departing from the scope of my invention, and I do not intend to limit myself to the exact construction, of the whole or any of the parts thereof herein set forth.

I claim:—

1. A blank to be used for forming collapsible receptacles or boxes comprising a 115 combined cover and tilting supporting base-portion, divided into a main central portion of substantially rectangular form; an outer securing portion extending from one side of such cover portion and divided therefrom by a scoring-line; a like narrow member on the opposite side of such cover portion divided therefrom by a scoring line parallel with the like line of scoring of the outer securing portion; a rear-wall member of the 120 same length as the cover portion, and of substantially the same width as the other securing portion, formed integral therewith and separated therefrom by a scoring-line; an end wall-portion, divided from the back- 125 130

- wall portion by a scoring-line extending in line with such back-wall portion and of the same width as such back-wall portion, a front wall-portion of the same length as the 5 back wall portion, separated from such side wall portion by a scoring line, and an end-wall portion adapted to be secured at the end to the free-end of the back wall-portion of the cover-portion, so as to be capable of 10 forming an outer binding-rectangle for an inner box-body portion.
2. A blank to be used for forming collapsible receptacles or boxes comprising a combined cover and tilting supporting base-portion, divided into a main central portion of substantially rectangular form; an outer securing portion extending from one side of 15 such cover portion and divided therefrom by a scoring-line; a like narrow member on the opposite side of such cover portion divided therefrom by a scoring line parallel with the like line of scoring of the outer securing portion; a rear-wall member of 20 the same length as the cover portion, and of substantially the same width as the other securing portion, formed integral therewith and separated therefrom by a scoring-line; an end-wall portion, divided from the back-wall portion and of the same width as such back-wall portion; a front-wall portion of 25 the same length as the back-wall portion, separated from such side-wall portion by a scoring line; and an end-wall portion, having a tab secured to the 30 free-end of the back-wall portion of the cover portion, so as to be capable of forming an outer binding-rectangle for an inner box-body portion.
3. A blank to be used for forming collapsible receptacles or boxes comprising a combined cover and tilting supporting base-portion, divided into a main central portion of substantially rectangular form; an outer 35 securing portion extending from one side of such cover portion and divided therefrom by a scoring-line; a like narrow member on the opposite side of such cover portion divided therefrom by a scoring line parallel 40 with the like line of scoring of the outer securing portion; a rear-wall member of the same length as the cover portion, and of substantially the same width as the other securing portion, formed integral therewith 45 and separated therefrom by a scoring-line; an end-wall portion, divided from the back-wall portion by a scoring-line extending in 50 line with such back-wall portion and of the same width as such back-wall portion, a front-wall portion of the same length as the back-wall portion, separated from such side-wall portion by a scoring-line; and an end-wall portion adapted to be secured at 55 the end to the free-end of the back-wall portion of the cover-portion, so as to be capable of forming an outer binding-rectangle for an inner box-body portion, bent up from a 60 separate blank, having a cover formed integral therewith.
4. A blank to be used for forming collapsible receptacles or boxes comprising a combined cover and tilting supporting base-portion, divided into a main central portion of substantially rectangular form; an outer 65 securing portion extending from one side of such cover portion and divided therefrom by a scoring-line; a like narrow member on the opposite side of such cover portion divided therefrom by a scoring line parallel 70 with the like line of scoring of the outer securing portion; a rear-wall member of the same length as the cover portion, and of substantially the same width as the other securing portion, formed integral therewith 75 and separated therefrom by a scoring-line; an end-wall portion, divided from the back-wall portion and of the same width as such back-wall portion; a front-wall portion of 80 the same length as the back-wall portion, separated from such side-wall portion by a scoring line; and an end-wall portion, having a tab secured to the free-end of the back-wall portion of the cover portion, so as to be capable of forming an outer binding-rectangle for an inner box-body portion, bent up from a 85 separate blank.
5. A blank to be used for forming collapsible receptacles or boxes comprising a combined cover and tilting supporting base-portion, divided into a main central portion of substantially rectangular form; an outer 90 securing portion extending from one side of such cover portion and divided therefrom by a scoring-line; a like narrow member on the opposite side of such cover portion divided therefrom by a scoring line parallel 95 with the like line of scoring of the outer securing portion; a rear-wall member of the same length as the cover portion, and of substantially the same width as the other securing portion, formed integral therewith 100 and separated therefrom by a scoring-line; an end-wall portion, divided from the back-wall portion by a scoring-line extending in 105 line with such back-wall portion and of the same width as such back-wall portion, a front-wall portion of the same length as the back-wall portion, separated from such side-wall portion by a scoring-line; and an end-wall portion adapted to be secured at 110 the end to the free-end of the back-wall portion of the cover-portion, so as to be capable of forming an outer binding-rectangle for an inner box-body portion, bent up from a 115 separate blank, having a cover formed integral therewith.
6. A blank to be used for forming collapsible receptacles or boxes comprising a combined cover and tilting supporting base-portion, divided into a main central portion of substantially rectangular form; an outer 120
- 125
- 130

securing portion extending from one side of such cover portion and divided therefrom by a scoring-line; a like narrow member on the opposite side of such cover portion divided therefrom by a scoring line parallel with the like line of scoring of the outer securing portion; a rear-wall member of the same length as the cover portion, and of substantially the same width as the other securing portion, formed integral therewith and separated therefrom by a scoring-line; an end-wall portion, divided from the back-wall portion and of the same width as such back-wall portion; a front-wall portion of 10 the same length as the back-wall portion, separated from such side-wall portion by a scoring line; and an end-wall portion, having a tab secured to the free-end of the back-wall portion of the cover portion, so as to 15 be capable of forming an outer binding-rectangle for an inner box-body portion, bent up from a separate blank, having a cover formed integral therewith.

7. A blank to be used for forming collapsible receptacles or boxes comprising a combined cover and tilting supporting base-portion, divided into a main central portion of substantially rectangular form; an outer securing portion extending from one side 20 of such cover portion and divided therefrom by a scoring-line; a like narrow member on the opposite side of such cover portion divided therefrom by a scoring line parallel with the like line of scoring of the outer securing portion; a rear-wall member of 25 the same length as the cover portion, and of substantially the same width as the other securing portion, formed integral therewith and separated therefrom by a scoring-line; an end-wall portion, divided from the back-wall portion and of the same width as such back-wall portion, a front-wall portion of 30 the same length as the back-wall portion, separated from such side-wall portion by a scoring line; and an end-wall portion, 35 having a tab secured to the free-end of the back-wall portion of the cover portion, so as to be capable of forming an outer binding-rectangle for an inner box-body portion, bent up from a separate blank, having five 40 scored lines and four front and back-wall securing tabs.

8. A blank to be used for forming collapsible receptacles or boxes comprising a combined cover and tilting supporting base-portion, divided into a main central portion of substantially rectangular form; an outer securing portion extending from one side 45 of such cover portion and divided therefrom by a scoring-line; a like narrow member on

the opposite side of such cover portion divided therefrom by a scoring line parallel with the like line of scoring of the outer securing portion; a rear-wall member of the same length as the cover portion, and 50 of substantially the same width as the other securing portion, formed integral therewith and separated therefrom by a scoring-line; an end-wall portion, divided from the back-wall portion by a scoring-line extending in 55 line with such back-wall portion; a front-wall portion of the same length as the back-wall portion, separated from such side-wall portion by a scoring line, and an end-wall portion adapted to be secured at the end 60 to the free-end of the back-wall portion of the cover-portion, so as to be capable of forming an outer binding-rectangle for an inner box-body portion, bent up from a separate blank, having a cover formed integral therewith, having five scored lines, 65 and four front and back-wall securing tabs.

9. A blank to be used for forming collapsible receptacles or boxes comprising a combined cover and tilting supporting base 70 portion, divided into a main central portion of substantially rectangular form, an outer securing portion extending from one side of such cover portion and divided therefrom by a scoring-line; a like narrow member on 75 the opposite side of such cover portion divided therefrom by a scoring line parallel with the like line of scoring of the outer securing portion; a rear-wall member of the same length as the cover portion, and 80 of substantially the same width as the other securing portion, formed integral therewith and separated therefrom by a scoring-line; an end-wall portion, divided from the back-wall portion and of the same width as such 85 back-wall portion; a front-wall portion of the same length as the back-wall portion, separated from such side-wall portion by a scoring line; and an end-wall portion, having a tab secured to the free-end of the 90 back-wall portion of the cover portion, so as to be capable of forming an outer binding-rectangle for an inner box-body portion, bent up from a separate blank, having a cover formed integral therewith, having five 95 scored lines, and four front and back-wall securing tabs.

Signed at the borough of Manhattan, county, city and State of New York, this 30 day of March, 1917.
